ATTORNEY.

UNITED STATES PATENT OFFICE.

EMANUEL RAWSON, OF CHICAGO, ILLINOIS, ASSIGNOR TO THE SUPERHEATER COMPANY, OF NEW YORK, N. Y.

AUTOMATIC CONTROL VALVE.

Application filed October 29, 1927. Serial No. 229,726.

My invention relates to automatic control valves, and has particular reference to the type of valve used to prevent the starting or continued operation of a fluid pressure driven pumping unit under no load conditions. Specifically, the invention is in the nature of an improvement upon the invention described and claimed in my copending application, Serial No. 217,118, filed September 2d, 1927, designed to improve the operating characteristics of the control valve under certain service conditions. The detailed objects of the invention, together with the advantages to be derived from its use, will appear from the following detailed description of a preferred form of the invention applied to a steam driven centrifugal pumping unit used as the feed water pump for a locomotive.

In the accompanying drawings forming a part hereof, Fig. 1 is a fragmentary elevation of a locomotive equipped with such a feed water pump to which the invention has been applied; Fig. 2 is an elevation, partly in section, on an enlarged scale showing the pump and valve assembly; and Fig. 3 is a section on a still larger scale of a detail of the apparatus.

Referring now to the drawings, the pumping unit indicated at 1 comprises a steam driven turbine rotor 2 directly connected to the vane of a centrifugal pump 3, the turbine and pump being mounted in a single housing. The turbine is supplied with steam through the conduit 4 controlled by the throttle 5 and having located therein the valve casing 6 between the throttle 5 and the turbine. The pump is supplied with water through the inlet conduit 7 and discharges through conduit 8 to the check valve (not shown) of the boiler.

The valve 9, adapted to control flow through the conduit 4, is mounted in the casing 6, the latter carrying a capped bonnet 10 forming a cylinder in which is located the piston 11 mounted on the end of the stem of valve 9. A spring 12 below piston 11 holds valve 9 normally in open position.

Between throttle 5 and valve 9 the inlet conduit 4 is provided with a manually operable vent valve 13, the purpose of which will appear hereinafter.

The casing 6 on the inlet side of valve 9 is provided with a restricted opening 14

from which the conduit 15 leads to the hydraulic control unit situated within the pump housing. The hydraulic control unit comprises a casing 16 forming a closed chamber 17 connected with the discharge side 60 of the pump 3 through the passages 18 and 19. The top of chamber 17 is defined by a flexible diaphragm 20 suitably secured in the casing 16, said diaphragm serving to support a cylindrical valve member 21 slidably mounted in the housing 16 and having a conically faced upper end adapted to engage a seat formed within the casing 16 to separate the chambers 22 and 23. Intermediate its ends the valve member 21 is provided with an annular recess registering with an atmospheric vent in casing 16 to prevent the building up of pressure on top of the diaphragm 20 due to leakage.

The conduit 15 leads from the restricted 75 opening 14 in casing 6 to the chamber 23 above the hydraulic valve member 21, and the lower chamber 22 is connected by means of a conduit 24 to the chamber above the piston 11 actuating the valve 9.

An automatic timing valve is located in conduit 24 and, as is shown more clearly in Fig. 3, the timing valve comprises a casing 25 forming a chamber 26 opening through the port 27 to the passage 28, the latter being connected by means of a suitable drain pipe 29 to the atmosphere. The conduit 24 is connected to chamber 26 so that the latter forms a part of the connection between the hydraulic control valve and the piston 11. The port 27 is controlled by a valve 30 resiliently held in open position by the spring 31, the latter being carried by a suitable recessed spider 32 forming part of the casing 25. As will be clear from Fig. 95 3, the valve 30 will be held in open position by the spring 31 until a predetermined pressure is built up in chamber 26, thereby providing an atmospheric vent for the conduit 24 when the pressure in the latter is below 100 a certain value. When the pressure in chamber 26 exceeds this value, it will serve to close valve 30 against the action of spring 31 to close the vent.

The operation of the device is as follows: 105 Assuming the pump not in operation with water available in the conduit 7, opening of the throttle 5 permits steam to flow to the pump turbine through the valve 9, which is held in open position by spring 12. At 110

the same time steam is permitted to flow into conduit 15 through the restricted opening 14, but due to the restriction the steam flow into the conduit is at a comparatively slow rate. Steam delivered by conduit 15 flows from chamber 23 to chamber 22 past the hydraulic valve member and enters conduit 24 leading to piston 11. The open timing valve 30, however, affords an atmospheric release of steam passing through chamber 26 until the pressure built up in the chamber is sufficient to close the valve 28, and appreciably delays the flow of steam through the remainder of conduit 24 to the chamber above piston 11.

During the interval of time before steam can reach piston 11, caused by the delay action of the restricted opening 14 and timing valve 30, the pump 3 builds up a discharge pressure which is communicated to the underside of diaphragm 20 and acts to lift the valve member 21 to shut off communication between chambers 23 and 22. It will thus be seen that if water is available at the suction side of the pump when the latter is started, steam flow to the piston 11 will be closed by the hydraulic valve member before a pressure is built up sufficient to overcome the action of spring 12 and close the valve 9 to shut off the steam supply to the pump. If operating conditions remain normal, that is, a continued supply of water is received by the pump, the apparatus will continue to operate in the manner just described with the hydraulic valve member 21 preventing the flow of steam to the control valve 9 and permitting continued steam flow to the turbine.

If, now, the water supply to the pump fails, the resultant lack of pressure in the pump discharge line will allow the valve member 21 to be forced downwardly by the pressure of steam in chamber 23, thus establishing communication between the conduit 15 and piston 11. The timing valve 30 in this instance will permit an initial escape of steam to the atmosphere, but upon the building up of pressure in chamber 26 this valve will close and steam will pass on through the conduit 24 to act on piston 11, closing valve 9 and shutting off the pump.

If for any reason the automatic valve 9 is closed, and the throttle 5 is subsequently closed, it will be seen that an appreciable quantity of steam under pressure will be trapped in the steam supply conduit 4 between the two valves, and the pressure of this steam communicated to the piston 11 through conduits 15 and 24 will serve to hold the valve 9 in closed position until the trapped steam condenses. Until such condensation takes place, it would be impossible to restart the pump, and in order to avoid such delays and make it impossible to immediately restart the pump after valve 9 has

been closed I have provided the vent valve 13 for the purpose of releasing this trapped steam and allowing the valve 9 to open.

If it is attempted to start the pump when no water is available in the conduit 7, the action of the control valve will be substantially the same as that previously described when the water supply fails with the pump in operation, as steam will pass immediately, except for the delay occasioned by restriction 14 and valve 30, through conduits 15 and 24 to the piston 11, and close the control valve 9.

The delay action provided is necessary to permit the starting of the pump when water is available, for if steam were permitted to flow without delay from the inlet conduit 4 to the piston 11, it would close the valve 9 and shut down the pump before the latter had had sufficient time to build up a hydraulic discharge pressure sufficient to actuate the valve member 21 and close communication between conduits 15 and 24.

The general arrangement of pump and control valve described is similar to that shown in my copending application hereinbefore referred to except for the provision of the timing valve 30, which I have found necessary to the satisfactory operation of the device under all conditions. In the prior form delay action was secured by means of an expansion chamber placed in the conduit 15, but under certain operating conditions the steam trapped in such a chamber will flow past the open valve 21 and close the main valve 9 when such action is not desired. With the present arrangement the amount of steam in conduit 15 is comparatively small, and this steam is vented to the atmosphere through valve 30 under conditions which permitted steam from an expansion chamber in conduit 15 to close the main valve 9.

For example, if the pump running under normal conditions is shut down by closing throttle 5, the action is as follows: The closing of the throttle causes an immediate drop in pressure in conduit 4, and also a very rapid loss of pressure in the chamber 17, permitting the valve 21 to open. The restriction 14 does not, however, permit a rapid return flow of steam from the conduit 15 to the conduit 4 in which the pressure has dropped, and this steam is free because of the opening of valve 21 to flow toward the piston 11. In cases where an expansion chamber is used, this steam is sufficient in quantity to actuate piston 11 and close valve 9, thereby preventing restarting of the pump until condensation of the steam takes place. With the present arrangement the small quantity of steam trapped in the conduit 15 will escape through the timing valve 30 and have no effect on piston 11.

It will be obvious that the amount of delay secured before steam reaches piston 11 will be determined by the strength of the spring 31 governing the action of the timing valve 30, and I have found that for centrifugal pumps of the type employed a spring pressure of about twelve pounds acting on valve 30 to hold it open gives the correct timing delay.

Furthermore, it will be evident that the timing valve may be placed in conduit 15 instead of conduit 24 without affecting the operation of the device, but I prefer to locate it in conduit 24, as in this position it is open when the pump is in normal operation, while if in conduit 15 it would be closed and subject to steam pressure whenever the pump operated.

Obviously, the control valve mechanism shown in the illustrative embodiment may be applied to many different forms of prime movers, and many changes and modifications in the specific arrangement shown may be made without departing from the spirit of the invention, which is to be considered as including all that may fall within the scope of the appended claims.

I claim:

1. An apparatus of the class described, a turbine, a pump driven thereby, a conduit connecting said turbine with a fluid pressure source, a throttle located in said conduit, a control valve located in said conduit between said throttle and said turbine, a fluid pressure actuated means for closing said control valve, a hydraulic control unit comprising a valve adapted to be closed by the discharge pressure from said pump, a connection leading from the inlet side of said control valve to the valve in said unit, a connection leading from said last-named valve to said pressure actuated means, an opening venting one of said connections to the atmosphere, and a valve controlling

said opening, said valve being closed by a predetermined pressure in said connections.

2. In apparatus of the class described, a turbine, a pump driven thereby, a conduit connecting said turbine with a fluid pressure source, a throttle located in said conduit, a control valve located in said conduit between said throttle and said turbine, fluid pressure actuated means for closing said control valve, a hydraulic control unit comprising a valve adapted to be closed by the discharge pressure from said pump, a connection leading from the inlet side of said control valve to the valve in said unit, a connection leading from said last-named valve to said pressure actuated means, an opening venting said last-named connection to the atmosphere, and a valve closed by a predetermined pressure in said last-named connection for controlling said opening.

3. In apparatus of the class described, a turbine, a pump driven thereby, a conduit connecting said turbine with a fluid pressure source, a throttle located in said conduit, a control valve located in said conduit between said throttle and said turbine, fluid pressure actuated means for closing said control valve, a hydraulic control unit comprising a valve adapted to be closed by the discharge pressure from said pump, a connection leading from the inlet side of said control valve to the valve in said unit, a connection leading from said last-named valve to said pressure actuated means, an opening venting said last-named connection to the atmosphere, a valve controlling said opening, said valve being constructed and arranged to be closed by fluid pressure in said connection, and a spring for holding said valve in open position until a predetermined pressure is reached in said connection.

EMANUEL RAWSON.
